UNITED STATES PATENT OFFICE

132,923

DESIGN FOR A COMBINATION HANDBAG AND CIGARETTE DISPENSER

Harry A. Adams, New York, N. Y.

Application March 10, 1942, Serial No. 106,132

Term of patent 3½ years

To all whom it may concern:

Be it known that I, Harry A. Adams, a citizen of the United States of America, residing in New York city, county of New York, and State of New York, have invented a new, original, and ornamental Design for a Combination Handbag and Cigarette Dispenser, of which the following is a specification, reference being had to the accompanying drawings, forming part thereof, wherein,

Figure 1 is a front elevational view of a combination handbag and cigarette dispenser showing my new design;

Figure 2 is an end elevational view thereof;
Figure 3 is a rear elevational, and
Figure 4 is a perspective view thereof in open position.

The characteristic features of my design reside in the handbag disclosed having a cigarette dispenser on the front thereof of the configuration, and ornamented as shown.

I claim:

The ornamental design for a combination handbag and cigarette dispenser, substantially as shown, and described.

HARRY A. ADAMS.
